Assistant Examiner — Rachel Voorhies

(74) Attorney, Agent, or Firm — Global Patent Operation; John A. Kramer

(57) **CLAIM**

The ornamental design for a display screen with graphical user interface for displaying test details of an engine control test, as shown and described.

DESCRIPTION

The FIGURE is a front view of a display screen with a graphical user interface showing our new design.

The broken lines illustrate the display screen and portions of the graphical user interface that form no part of the claimed design.

1 Claim, 1 Drawing Sheet
